UNITED STATES PATENT OFFICE.

KLAS WEMAN, OF NEW YORK, N. Y.

ESCUTCHEON-PLATE AND LOCK FOR TELEPHONES.

SPECIFICATION forming part of Letters Patent No. 772,986, dated October 25, 1904.

Application filed August 25, 1903. Serial No. 170,707. (No model.)

To all whom it may concern:

Be it known that I, KLAS WEMAN, a subject of the King of Sweden and Norway, and a resident of the city, county, and State of New York, have invented a new Combined Escutcheon-Plate and Lock for Telephones, of which the following is a specification.

My invention refers to combined escutcheon-plates and locks on telephones, and is particularly applicable to what is known as "wall-telephones."

The object of my invention is to construct an escutcheon-plate which will at the same time serve as a lock, operating automatically without the aid of a key, and thus prevent the possibility of losing the key.

Previous to my invention it has been customary to use locking devices which require a key or necessitate the withdrawing of one or more screws before the door or lid can be opened. The key is often lost, and the undoing and tightening of screws take unnecessary time. Where my invention is applied, no key is needed, and the door or lid may be automatically closed and locked. The simple means by which this result is attained are fully described and explained in this specification and illustrated by the attached drawings, forming part thereof.

Like letters of reference designate like parts on the drawings.

Figure 1 represents a front elevation of my invention; Fig. 2, a top view thereof. Fig. 3 shows the invention applied on the telephone-box, the door being open; and Fig. 4 is a view showing details.

Referring to the drawings, the letter A designates the larger plate, intended to be fastened on the stationary part of the telephone by means of screws or the like entering the holes f, g, and h. This plate is recessed at m in order to permit the movement of the telephone switch-hook.

B is the smaller plate of the locking device and is secured to the movable part of the telephone. The plate B is angular in shape and is secured by screws or the like to the inner side of door or lid O.

C, Fig. 2, is a knob or projection attached

to the spring D. The spring D is soldered to or may be formed integrally with the plate B at N and further secured thereto when mounted by a screw entering the hole 1, Fig. 4. The spring D is slightly bent in order to make its operation more effective. When the pieces are mounted on a telephone-box, as illustrated by Fig. 3, and the door O is closed, the knob C, having its outer edge rounded off, will slide along the back surface of the plate A till it reaches the hole E, which it will enter and will then be forced through said hole E by the pressure of the spring D. The inner edge of the knob C is full and sharp. The pressure of the spring D will prevent the knob C from slipping out of the hole E when force is applied to open the door unless at the same time the knob C is pressed inward, in which case the edge of the knob C will pass the inner edge of the plate A, thereby releasing the door O.

It is obvious that the appliance may be changed to suit different types of telephones where the opening of a door or lid is desirable. It is also obvious that the knob C may be made square or oblong and the hole E of a similar shape.

I do not wish to be limited to the details shown in the drawings, as these may be modified in several particulars without departing from the spirit of my invention.

Having thus described my invention, what I claim as new, and desire to secure by Letters Patent is—

1. In combination, in a combined escutcheon-plate and lock for telephones, a member rigidly attached to the telephone-box adjacent one edge thereof, and having a recess in one edge to accommodate the switch-hook, and an opening through its body to one side of the recess, a second member of angular shape in cross-section having one part secured to the under side of the movable section or cover of said box, and its other part designed to abut against the edge of the first member, and an angular resilient arm having one part secured to the first part of the second member and having further a free end carrying a knob to engage the wall of the opening in the first

member, said arm being entirely hidden behind said two members when the cover is closed, substantially as described.

2. In a combined escutcheon-plate and lock 5 for telephone-boxes, a plate secured to the body of the box near one edge of the same and having a recess to accommodate the switch-hook, and an opening to one side of said recess, a spring-arm secured to the cover of the 10 box and extending at right angles therefrom,

and a knob at the free end of the arm engaging the wall of the opening in said plate, said arm being entirely hidden when the cover is closed, substantially as described.

In witness whereof I have hereunto set my 15 hand in presence of two witnesses.

KLAS WEMAN.
